UNITED STATES PATENT OFFICE.

CHARLES SEYBOLD, OF DAYTON, OHIO.

PAPER-CUTTING MACHINE.

1,100,000.

Specification of Letters Patent. Patented June 16, 1914.

Application filed December 22, 1913. Serial No. 808,062.

To all whom it may concern:

Be it known that I, CHARLES SEYBOLD, a citizen of the United States, and a resident of the city of Dayton, in the county of 5 Montgomery and State of Ohio, have invented certain new and useful Improvements in Paper-Cutting Machines, of which the following is a full, clear, and exact description, reference being had to the accompanying drawings, forming part of this specification.

My invention relates to paper cutting machines and consists of that certain novel construction and arrangement of parts to be 15 hereinafter particularly pointed out and claimed whereby economy of construction is combined with efficiency in operation to furnish a most powerful and effective machine at a minimum cost of manufacture.

20 One of the principal features of my invention relates to the construction of clamp operating mechanism whereby the friction clutch which must necessarily be employed in coupling the power to the clamp is applied to the driving member of the machine and not to the driven member. Heretofore in all power operated machines with power clamp, the friction clutch for the clamp has been applied to the driven member of 25 the clamp mechanism, so that the slip, when the clamp has reached and compressed the paper pile, takes place directly between the clamp and the member operating it. It follows from this that to obtain a hundred pounds pressure for the clamp, the friction clutch must be capable of holding up one hundred pounds.

In my present invention, I have applied the 30 friction clutch to the driving member and not to the driven member, so that by proper leverage between the driving and driven members, the application of twenty five pounds pressure on the friction clutch will hold one hundred pounds pressure on the 35 clamp, and in this way a ratio of four to one, or any other desired ratio can be established. In addition to this improvement on the application of the clutch mechanism, I also arrange to connect the clamp member with 40 the driving mechanism only on the down-stroke, the clamp being balanced by weight for the up-stroke so that it can be returned to its operative position without the expenditure of any power; while in the ordinary constructions the clamp is usually driven by a rack and segment which is continuously in

mesh so that the machine power raises as well as lowers the clamp member.

Another feature of my invention relates to the knife construction whereby a much stiffer knife can be provided with a decreasing liability to bend under strains. As ordinarily provided, a knife is furnished of sufficient width to permit of grinding away the knife surface for sharpening, and therefore to provide for this the knife is usually secured to the knife carrier or frame so that its cutting edge extends some considerable distance beyond the holding frame. To overcome this objection, I attach the knife so the cutting edge is closer to the carrier as to give great stability, and as the knife is worn down in grinding, I provide for the insertion of metal strips to abut against the back edge of the knife, and extend the knife edge beyond the carrier, and I arrange for a series of bolt holes in the knife blade for the attachment.

Another feature of improvement relates to the friction clutch construction whereby the clutch may be readily and easily adjusted for the application of increased clamping power at a moment's notice, and if at the same time the clutch be set too tight for the required friction, the pulling screw rod, which is purposely twisted, is intended to stretch should too great a strain be thrown on the clutch. Provision is also made to prevent the breakage of any of the machine mechanism should the same be subjected to extraordinary strain of any kind, by means of the construction in which I couple the power shaft to the driving mechanism of the machine through the medium of a grooved washer, which washer is the weakest piece in the train of mechanism, so that the washer will break and cut off the driving power before any further damage can be done under undue strains.

Other features of novelty and importance 100 will be more particularly pointed out in connection with the description.

In the drawings, Figure 1 is a side elevation of the right hand side of my machine, being the side upon which power is 105 applied. Fig. 2 is a similar side elevation of the opposite side of the machine, a portion of the frame broken away. Fig. 3 is a front elevation. Fig. 4 is a central section of the friction clutch. Fig. 5 is a side 110 view of the same showing portions broken away. Fig. 6 is a front elevation of the

friction clutch. Fig. 7 is a perspective view showing the method of securing the knife to the knife carrier. Fig. 8 is a perspective view of one of the extension bars for the knife. Fig. 9 is a perspective view of the inner end of the power shaft. Figs. 10 and 11 are perspective views respectively of the driving pinion and the grooved washer connecting same to the power shaft.

10 The operating parts of the paper cutter are mounted in a solid and substantial casting 1, forming supporting standards and framework for the various shafts and operating mechanism of the machine. For 15 economy of construction, all of the bearings for the various shafts are located in alignment in this single casting, so that a united structure is provided which can be easily finished for the support of all the necessary 20 purposes, instead of requiring cross pieces and side bearings. Mounted in suitable bearings in this framework is the driving shaft 2 for the machine, which receives its power from the power shaft 3 connected by 25 a belt 4 and pulley 5 with any suitable source of power, the driving power being communicated through a train of gears and pinions 6, 7, 8, to the gear 9 keyed to the driving shaft 2.

30 The knife carrier 10, arranged to reciprocate in suitable guide slots 11, 11 in the side plates 12, 12 of the framework, is coupled, at each end outside the framework by the pulling bars 13, 13, with crank pins 35 14, 14 on each end of the driving shaft 2 of the machine, under the rotation of which the knife carrier and the knife attached thereto is reciprocated in the operation of the machine. The usual power clamp is indicated by dotted lines 15 in Fig. 2, and arranged to be reciprocated in connection with the knife to clamp the paper pile, and to be raised again to normal elevated position with each operation of the machine.

40 This clamp bar is suitably guided between the side plates 12, 12, and carries at each end a downwardly projecting bar 16, 16. These bars each carry an outwardly projecting stud or pin 17 which is engaged by a 45 bifurcated arm 18, each pivoted to the crank arm 19 at either end of a rock shaft 20 suitably journaled in the base casting. This rock shaft 20 carries the gear 21 secured thereon, and this gear meshes with a 50 segment gear 22, which is loosely mounted on the driving shaft 2 of the machine. The hub 23 of this segment gear (Fig. 4) is formed with a friction disk 24, the periphery of which is provided with a friction 55 band 25 of leather, or other suitable material, and this band is engaged by a split friction ring, suitably leather-lined, and made up of two halves 26 and 27. This split friction ring is connected at its lower 65 portion by the bolt 28, passing through the

lugs 29, 30, on the two halves, and provided with a tension coiled spring 31. The opposite end of the half ring 26 is provided with a boss 32, in which is mounted a twisted pulling screw rod 33, adjustable by the 70 knurled nut 34. The opposite end of this twisted pulling screw rod 33 engages a crank arm on the crank pin 35, the crank pin being journaled in a corresponding boss 36 on the opposed half of the friction ring 75 27. The crank pin 35 passes loosely through a suitable opening in the disk plate 38, which plate is keyed on the shaft 2.

The crank pin 35 on the outer face of the disk 38 is provided with a crank arm 39 carrying at its lower depending end a roller 40 which roller bears on the cam surface of a cam 41, which cam is loosely mounted on the driving shaft 2. The cam 41 is provided with a lateral extension plate 42 which is flat and bears against the frame casting 1 at each end, so as to prevent the cam from turning. The cam is loose on the shaft 2 to slide longitudinally, and the cam is provided with two bearing surfaces 43 and 44, so that either may be brought into operative connection with the roller 40 on the crank arm 39. The cam is shifted by oscillating the handle 45 which is mounted on the segment plate 46, pivoted at 47 to the frame and carrying an arm 48 with a stud 49 to engage a grooved projection on the hub of the cam 41. One of the cam surfaces on this cam is considerably higher than the other, and as either cam is in operative position, with the rotation of the shaft 2 the crank arm 39 will be oscillated to rock the crank pin and to draw tight or loosen the split friction ring. The disk plate 38 being keyed on the shaft 2, with each rotation of the shaft, the crank arm 39 with its roller 40 is carried around the cam surface and the cam surface is so arranged with relation to the movements of the machine that the friction will be applied to the friction ring to couple the segment driving gear 22 to the shaft 2 only during the down-stroke of the clamp rock shaft 20 with which the segment gear is in connection through the gear 21. The clamp is suspended by chains running over pulleys 100 105 110 115 120 125 130 and having at the lower end a weight to balance the weight of the clamp, and in order to raise the clamp after it has been brought down on the paper by the rocking of the rock shaft 20 through the medium of the bifurcated arms 18 bearing on the pins 17 and to return the rock shaft to normal position, I provide a cam 50 mounted on the driving shaft 2, which cam engages a roller 51 on one end of the bell crank lever 52, 125 130 journaled at 53 in the base. The outer arm of this lever is coupled to a lifting bar 54, pivoted on the arm 19 of the rock shaft 20. The action of the cam is so timed that after the clamp has been brought down on

stroke, the clamp will be released and thereupon the cam 50 on the driving shaft will return the rock shaft to its normal position, and the weight descending will raise the clamp to its normal position. Should it be desired to obtain greater clamping pressure, this can be at once provided for by shifting the handle 45 to slide the cam 41 lengthwise on the shaft to bring the cam surface 44 in contact with the roller 40 on the crank arm 39. If in tightening up the friction clutch by the screw 34, the adjustment is made too tight, instead of too great a friction being applied, the twisted screw rod will stretch 15 without damage to the machine.

Having thus described my invention, what I claim as new and desire to secure by Letters Patent, is:—

1. In a paper cutting machine, the combination with the cutting knife and the clamp for holding the paper pile, of a driving member for the knife and a member driven thereby for the clamp, with a friction clutch device coupled to the driving member and connection therefor with the driven member whereby the clamping power may be increased in any desired proportion to the power of the friction clutch.

2. In a paper cutting machine, the combination with the cutting knife and the clamp for holding the paper pile, of a driving shaft and connecting mechanism for the knife, means for actuating the clamp and connection therefor with the driving shaft and a friction clutch mounted on the driving shaft intermediate the clamp connections, whereby the clamping power may be increased in any desired proportion to the power of the friction clutch.

3. In a paper cutting machine, the combination with a driving shaft and a driven shaft, of cutting mechanism coupled to the driving shaft and a clamp coupled to the driven shaft, a friction clutch mounted on the driving shaft and train of gearing connecting the driving and the driven shafts through the friction clutch, whereby the clamping power may be increased in any desired proportion to the power of the friction clutch.

4. In a paper cutting machine, the combination with a driving shaft and a driven shaft, of cutting mechanism coupled to the driving shaft and a clamp coupled to the driven shaft, a train of gearing intermediate the two shafts, with friction clutch, one member connected to the driving shaft and the other member to the gear train, whereby the clamping power may be increased in any desired proportion to the power of the friction clutch.

5. In a paper cutting machine, the combination with a driving shaft and a driven shaft, of cutting mechanism coupled to the driving shaft and a clamp coupled to the

driven shaft, a train of gearing intermediate the two shafts, with the driving gear loosely mounted on the driving shaft and a clutch to couple said gear to the driving shaft.

6. In a paper cutting machine, the combination with the cutting knife and the clamp for holding the paper pile, of a driving member for the knife and a member driven thereby for the clamp, with a friction clutch device intermediate the two members, said friction clutch comprising a split ring, and a disk engaged thereby, with means for automatically clamping said split ring on the down-stroke of the knife.

7. In a paper cutting machine, the combination with the cutting knife and the clamp for holding the paper pile, of a driving member for the knife and a member driven thereby for the clamp, with a friction clutch device intermediate the two members, said friction clutch comprising a split ring, and a disk engaged thereby, with means for automatically clamping said split ring on the down-stroke of the knife, and means for releasing the split ring on the up-stroke of the knife.

8. In a paper cutting machine, the combination with the cutting knife and the clamp for holding the paper pile, of a driving member for the knife and a member driven thereby for the clamp, with a friction clutch device intermediate the two members, said friction clutch comprising a split ring, and a disk engaged thereby, a crank for clamping the split ring, and a cam for actuating said crank to operate same in timed relation to the knife movement.

9. In a paper cutting machine, the combination with the cutting knife and the clamp for holding the paper pile, of a driving member for the knife and a member driven thereby for the clamp, with a friction clutch device intermediate the two members, said friction clutch comprising a split ring, and a disk engaged thereby, a crank for clamping the split ring, and a cam for actuating said crank to operate same in timed relation to the knife movement, said cam provided with a plurality of cam surfaces for varying the throw of the crank and means for shifting either of said cam surfaces into operative position.

10. In a paper cutting machine, the combination with the cutting knife and the clamp for holding the paper pile, of a driving member for the knife and a member driven thereby for the clamp, with a friction clutch device intermediate the two members, said friction clutch comprising a split ring, and a disk engaged thereby, a crank for clamping the split ring, and a cam for actuating said crank to operate same in timed relation to the knife movement, said cam provided with a plurality of cam surfaces for varying the throw of the crank and adapted

the paper and the knife has been reciprocated to sever the pile, the cam will then come in contact with the roller 51 and rock the rock shaft 20 back to its normal position, and the clamp being thus freed from contact with the clamp-actuating mechanism, will be carried back to its normal raised position by the weight. A foot treadle 55 is also provided with a chain 56 which is coupled to the weight so that when it is desired to cause the clamp to rapidly approach the paper, the depression of the foot lever will raise the weight and allow the clamp to descend under its own weight. 15 The return of the rock shaft to its normal position by the action of the cam 50 also rotates the gear 21 and the segment gear 22. The action of the cam 43 on the driving shaft 2 is so timed with relation to the other 20 movements of the machine that the friction clutch is only applied during the down-stroke of the machine; with the upstroke the friction clutch is released.

The arrangement heretofore described by 25 which the lower ends of the split friction ring are held together by the bolt 28 and the coiled spring 31 still maintains, however, some frictional contact between the disk of the segment gear 22 and the driving shaft 2. 30 In this way, the friction clutch acts as a brake in rocking the rock shaft 20 back to its normal position, and prevents pounding.

In order that the cutting knife 57 (Fig. 7) may always be held rigidly against the 35 frame plate 58, I provide a knife with a series of three sets of bolt holes 59 for attachment to the knife carrier, and in connection with the knife I provide two or more bars 60, 61, of different widths. When 40 the knife is first secured to the knife carrier, these bars are omitted and the knife bolted through the lower set of holes, bringing the cutting edge of the knife only a short distance below the support. As the knife is 45 ground down in sharpening, I secure the knife to the knife carrier in the middle set and then in the upper set of holes and employ therewith one of the bars 60 or 61 to fill out the width of the knife. In this way, 50 the knife may be at all times maintained rigid and in close contact with the knife carrier frame.

In order to insure the machine against 55 breakage of any of the gears or the other operating mechanism, I couple the power shaft 3 with the driving pinion 6 by means of a grooved washer 62 (Fig. 11). The driving pinion 6 is loosely mounted on the power shaft 3, and the end of this power 60 shaft is provided with a tongue or tenon 63 to be brought in alinement with the tenons 64, 64 on the side face of the pinion 6, and the pinion and shaft are then locked together by the washer 62 with its groove 65 engaging the tongues on the shaft and

pinion, and the parts are held together by a screw. This washer 62 is purposely made the weakest piece in the machine, and therefore, if there is any undue strain thrown on the mechanism, this washer will break and thus uncouple the power shaft 3. 70

For starting the machine and stopping it at the end of each operation, the usual hand lever 66 is provided for rocking the shaft 67. This shaft carries the usual clutch 75 actuating mechanism, indicated generally without detailed description at 68 in Fig. 1, which clutch actuating mechanism throws into and out of operation the driving clutch mechanism by which the pulley is coupled 80 to the driving shaft 3. This actuating lever 66 is also connected by the link 69 and lever 70 with the roller 71 (Fig. 3) which bears upon the cam disk 72 which is mounted on the driving shaft 2, so 85 that with each rotation of the driving shaft 2 the rock shaft 67 is rocked back to its normal position to release the driving clutch mechanism and thus stop the machine. I have not thought it necessary to describe in 90 detail the starting and stopping mechanism, as this forms no part of my present invention.

The operation of the machine will be evident from the foregoing description. The 95 pile of paper to be cut is located on the table top 73 and properly adjusted against the back gage (not shown). The clamp is lowered to the pile by its own weight, the operator depressing the foot treadle 55 to raise the balance weight which is connected to the clamp by chains running over pulleys. The details of this construction are not shown, as they are old and familiar in the 100 art. The operator then by shifting the hand lever 66, throws the power clutch into operation to connect the machine mechanism with the driving pulley, and the rotation of the driving pulley through the train of gearing rotates the driving shaft 2 of the machine. 105 The cam surfaces on the cam 41 are so arranged that before the knife has reached the pile of paper to be cut, the crank arm 39 will be rocked to draw together the split friction ring and frictionally couple the 110 segment gear 22 to the driving shaft. Under the movement of the driving shaft, the segment gear rocks the rock shaft 20 and the clamp compresses the paper within the 115 limits of the holding power of the split friction ring. Inasmuch, however, as the friction clutch is applied to the driving shaft 2, by reason of the leverage of the parts, very much less frictional hold is demanded of the friction clutch to give the maximum 120 power of compression to the clamp than if the friction clutch was applied directly to the driven members of the clamp.

The cam surfaces of the cam 41 are so 125 arranged that on the completion of the knife 130

to be shifted longitudinally of the driving member to bring either of said cam surfaces into operative position.

11. In a paper cutting machine, the combination with a driving shaft and a rock shaft, of cutting mechanism coupled to the driving shaft, crank arms on the rock shaft with slotted arms coupled thereto, a clamp for the paper pile and connection therefor with the slotted arms, and a train of gearing intermediate the rock shaft and the driving shaft for actuating the rock shaft to depress the clamp.

12. In a paper cutting machine, the combination with a driving shaft and a rock shaft, of cutting mechanism coupled to the driving shaft, crank arms on the rock shaft with slotted arms coupled thereto, a clamp for the paper pile and connection therefor

with the slotted arms, and a train of gearing intermediate the rock shaft and the driving shaft for actuating the rock shaft to depress the clamp, with a cam on the driving shaft or gear and connecting levers actuated thereby to return the rock shaft and clamp to normal position.

13. In a paper cutting machine, a knife carrier, and cutting knife to be attached thereto, the cutting knife provided with a plurality of rows of holes for attaching the knife in varying positions, and a series of bars of varying widths to serve as a backing for the knives, one for each adjustment.

CHARLES SEYBOLD.
